CLAIM

The ornamental design for a head for a quick-change filter cartridge, as shown and described.

DESCRIPTION

FIG. 1 is a top rear perspective view of a head for a quick-change filter cartridge showing our new design;
FIG. 2 is a top front perspective view thereof;
FIG. 3 is a bottom front perspective view thereof;
FIG. 4 is a top plan view thereof;
FIG. 5 is a rear elevational view thereof;
FIG. 6 is a front elevational view thereof;
FIG. 7 is a left side elevational view thereof;
FIG. 8 is a right side elevational view thereof;
FIG. 9 is a bottom plan view thereof;
FIG. 10 is a cross-sectional view thereof, taken on line 10—10 of FIG. 4;
FIG. 11 is a cross-sectional view thereof, taken on line 11—11 of FIG. 10; and
FIG. 12 is a cross-sectional view thereof, taken on line 12—12 of FIG. 10.
